EXPLOSIVELY DRIVEN STUD HAVING SEALING
AND RETAINING MEANS

Charles R. Webber and Virginius R. Erickson, Portland, Oreg., assignors, by mesne assignments, to Joseph B. Cox, doing business as Powder Power Tool Co., Portland, Oreg.

Original application December 31, 1949, Serial No. 136,186, now Patent No. 2,637,241, dated May 5, 1953. Divided and this application April 1, 1953, Serial No. 346,076

2 Claims. (Cl. 85—10)

This application is a division of copending application, Serial No. 136,186, filed December 31, 1949, now Patent No. 2,637,241, for Stud for Explosive Installation.

The present invention relates to stud driving tools of the type employed for installing studs by explosive action in wall surfaces, such as concrete and steel, and is concerned more particularly with the provision of an improved stud and method facilitating such driving and which facilitates the controlling of the effective power or force applied to the stud from a standard explosive charge.

In accordance with the instant invention the stud is provided on its head with a frictional portion or element preferably of a destructible material to hold the stud at a selected position along the barrel of the tool so that the desired effective force from a standard explosive charge will be applied to the stud. At the same time the frictional element being of a removable or destructible character, is readily destroyed so that it is no longer a part of the stud at the time the stud is installed in the wall surface.

The above and other objects of the invention are attained in a preferred embodiment of the invention as described in connection with the accompanying drawings, in which:

Figure 1 is an elevational view of a stud driving tool employing the invention, with a portion of the tool adjacent the combustion chamber broken away and shown in section to illustrate details of construction.

Figure 2 is a detailed enlarged view of a stud embodying the invention.

Figure 3 is a transverse sectional view of the stud taken as indicated by the view 3—3 in Figure 2.

Figure 4 is an enlarged view of the stud as mounted in the barrel of the tool.

Referring to Figure 1, there is shown a stud driving tool of the character described and claimed in the copending applications of Smith and Daugherty, Serial No. 124,078, filed October 28, 1949, for Stud Driving Tool, and Erickson and Bullwinkle, Serial No. 130,818, filed December 2, 1949, now Patent No. 2,679,645, for Stud Driving Tool. In general, stud driving tools of this character are adapted to be separated or broken into two halves including a rear half 10 which contains the various firing control parts including, for example, a firing pin carrier 11, and a front or barrel half 12 of the tool in which the barrel 13 is included. The barrel 13 is provided with an enlarged rear end 13a which has a threaded connection within the end of the firing pin carrier 11 to connect the two halves of the tool. The barrel 13 is also provided with an enlarged bore to receive a removable breech plug 14 in which the explosive cartridge 15 is mounted for impact by the firing pin of the firing mechanism. With the parts dis-assembled, the breech plug 14 is removed and the selected stud 17 is installed in the barrel, the cartridge 15 is placed in the breech plug 14, and the parts are reassembled as shown in Figure

2

1 for a firing operation. Firing is accomplished by placing the end of the barrel 13 against the surface into which the stud is to be driven and pressing or telescoping the barrel assembly 12 and the firing pin carrier 11 back into the other portions of the tool until a firing position is reached, as disclosed in said applications, and then effecting relative turning movement of the central housing and the end grip 18 to fire the tool. At this time the deflector pad structure 19, yieldably mounted about the barrel 13, is engaged with the surface about the area of engagement of the end of the barrel so as to provide protection from flying particles of the wall surface upon explosive installation of the stud.

Referring in particular to Figures 1, 2 and 3, the stud 17 is of special construction and carries with it a frictional portion or element on its head which is used to frictionally hold or secure the stud in a selected adjusted position in the barrel in accordance with the disclosure of the co-pending application of Virginius R. Erickson and Benjamin B. Bullwinkle, Serial No. 135,744, filed December 29, 1949, now Patent No. 2,722,003, for Stud Driving Tool and Method of Power Control.

The stud 17 includes the usual sharpened hardened point 17a and the head, which in this case is threaded as indicated at 17b. At the outer end of its head the stud is provided with an adhesively secured plastic disk or ring 21 whose external diameter is such as to be deformed as shown in Figure 4 when installed in the barrel of the gun. This disk 21 not only serves as a frictional retainer for the stud but also serves initially as a seal against which the explosive gases impinge upon trying to pass between the threaded portion of the stud and the barrel. The disk 21 may be constructed of any suitable material such as paper, plastic, rubber or the like, to be readily removable or destructible, but is preferably of resilient sheet plastic material such as cellulose acetate which is readily combustible so that the disk will be destroyed by burning during the expelling of the stud from the tool.

40 The material of the frictional retainer is preferably such that it is either completely consumed by the heat of the explosion, or is charred or carbonized sufficiently thereby as to be friable and easy to remove from the stud.

45 From the preceding it is seen that the method of holding a stud in place in the bore of the stud driving tool is carried out by effecting frictional engagement between the head of the stud and the bore of the tool, and this frictional engagement may be effected by placing a frictional disk, of the character disclosed in the drawing, 50 on the stud prior to the time of installation in the bore of the stud driving tool. This installation is preferably carried out by pushing the stud with the retainer thereon into the bore so that the retainer on the head serves to hold the stud in place against sliding movement in either direction until the time of firing the tool. While the studs are usually supplied by the manufacturer with the frictional retainer in place thereon, such frictional retainers may be supplied separately and placed by the 55 worker on the stud just prior to the time of installation in the bore of the tool.

60 While we have shown and described certain preferred embodiments of the invention it will be apparent that the invention is capable of both modification and variation from the form shown so that the scope thereof should be limited only by the scope of the claims appended hereto.

We claim:

65 1. A stud for insertion into the surface of a work piece by its ejection through the bore of an explosively actuated driving tool, said stud comprising a body having a cylindrical head at one end for slidably guiding and

supporting engagement within said bore and a surface penetrating shank of smaller diameter than said head at its other end, the head providing a shoulder to limit the penetration of the shank, and a deformable frictional retainer of destructible material adhesively secured on the head end of said stud in surface-to-surface engagement therewith and having a thin edge portion extending outwardly of the perimeter of the head, whereby said retainer when the stud is inserted in the bore of said explosively actuated tool through the breech end thereof will be deformed from its initial shape to frictionally retain said stud in any selected position along the bore and having a sealing effect on the explosive charge used to eject the stud.

2. A stud for insertion into the surface of a work piece by its ejection through the bore of an explosively actuated driving tool, said stud comprising a body having a cylindrical head at one end for slidably guiding and supporting engagement within said bore, and a surface penetrating shank of smaller diameter than said head at its other end, the head thereby providing a shoulder to limit the penetration of the shank, and a deformable destructible disc-like retainer adhesively secured on the head end of said stud in surface-to-surface engagement

therewith and having a thin edge portion extending outwardly of the perimeter of the head and bendable in a direction extending axially of the stud upon insertion of the stud into the bore, said edge portion providing for 5 sliding movement of the stud in either direction in said bore, whereby said retainer when the stud is inserted into the bore of the explosively actuated tool through the breech end thereof will be deformed from its initial shape to frictionally retain said stud in any selected 10 position along the bore and having a sealing effect on the explosive charged used to eject the stud.
